UNITED STATES PATENT OFFICE

ALEXANDER LOUVIER AND MARIUS LEWIS LOUVIER, OF PORT ARTHUR, TEXAS

WASHING MACHINE

Application filed February 16, 1932. Serial No. 593,338.

This invention relates to the class of washing machines and pertains particularly to a washing machine of the hand operated type.

The primary object of the present invention is to provide a new and novel type of hand operated washing machine in which a rotatable agitator is employed which may be removably positioned in a tub of clothes mounted upon a suitable support, the rotation 10 of the agitator being controlled by the reciprocatory movement of a hand lever.

Another object of the invention is to provide a washing machine having a rotatable agitator mounted upon a supporting beam 15 which is pivotally mounted to facilitate the raising or lowering of the agitator relative to a tub in which it is operated.

Other objects and advantages of the invention will become apparent as the description 20 of the same proceeds and the invention will be best understood from a consideration of the following detailed description taken in connection with the accompanying drawings forming part of this specification, with the 25 understanding, however, that the invention is not confined to any strict conformity with the showing of the drawings but may be changed or modified so long as such changes or modifications mark no material departure 30 from the salient features of the invention as expressed in the appended claims.

In the drawings:—

Figure 1 is a view in side elevation of the machine embodying the present invention, 35 showing a tub associated therewith and in section;

Figure 2 is a view in top plan of the washer;

Figure 3 is a sectional view taken on the line 3—3 of Figure 1;

Figure 4 is a sectional view taken on the line 4—4 of Figure 1.

Referring now more particularly to the drawings wherein like numerals of reference indicate corresponding parts throughout the 45 several views, the numeral 1 indicates generally a tub supporting base having forward supporting legs 2 and rear supporting legs 3.

The rear legs 3 are obliquely disposed with respect to the base and extend there- 50 through beyond the top surface thereof to

provide the posts 4 against the upper end of each of which is abutted and secured the brace beam 5 which extends downwardly through the base 1 and forwardly to the front supporting legs 2 in the manner illus- 55

trated in Figure 1. Extending transversely of the structure between the upper ends of the posts 4 and the brace beams 5 and secured thereto is a sill beam 6 to which is attached adjacent each end one leaf of each of a pair of hinge members 7. The other leaves of these hinge members are connected to a beam 8 which normally overlies the sill 6 and extending transversely of this last beam adjacent the transverse center thereof and secured thereto, is a relatively long arm beam 9, the forward end of which overlies the forward portion of the base 1. The rear end of the beam arm 9 extends beyond the rear of the base 1 as shown, and carries a hook 10 which is designed to be engaged with the eye 11 when the arm 9 is oscillated in one direction on its hinged supports, to maintain the forward end raised. 70

At its forward end the beam arm 9 has extended therethrough the vertically disposed spindle 12 which is rotatable in the beam and has a suitable connection at its lower end with the under face of the beam 80 as illustrated in Figure 3.

Surrounding this spindle 12 is a wear plate or washer 13 and above the washer is a pulley 14 through the axial center of which the spindle 12 passes and to which the spindle 85 is secured in any suitable manner.

At its lower end the spindle 12 is secured to the head block 15 of an agitator from which there extends downwardly the divergent fingers 16.

At the rear end of the device there is mounted upon the base 1 the pivot block 17 to which is pivotally connected by means of the bars 18 the hand lever 19. Pivotally connected to this hand lever by any suitable means such for example as the plate element 20, and at an elevation above the arm 9, is a reciprocable rod 21, the inner face of which tapers slightly to its free end as is clearly shown in Figure 2. This tapered in- 90 95 100

ner face of the rod 21 has connected thereto at a point substantially midway between its ends, as indicated at 23, one end of a rope or cable 24 which is wound several times about 5 the pulley 14 and has its other end attached to the free end of the rod 21 as illustrated in Figures 1 and 2.

In use a tub such as is indicated at 25, in which the clothes or other articles are to be 10 washed, is placed upon the base 1 beneath the agitator fingers 16, the latter having been shifted to the raised position indicated in dotted lines in Figure 1.

When the agitator element has been shifted 15 to this position it may be retained by connecting the hook 10 with the eye 11 in the manner illustrated. After the tub 25 has been supplied with the articles to be washed and the other necessary elements, the arm 9 is 20 lowered so as to bring the fingers 16 into the tub and the washing operation is then carried out by the operator working the lever 19 backward and forward thus causing the cable or rope 24 to rotate the pulley 14 and 25 consequently the spindle 12 with which the fingers are connected.

From the foregoing it will be readily apparent that the washing machine structure of the character herein described may be 30 easily and economically put up and so designed that it may be operated without a great expenditure of energy, thus making it possible for a woman to make use of the same.

Having thus described the invention, what 35 is claimed is:—

1. A hand operated washing machine comprising a base structure in the form of a platform, supporting legs for the platform at the front and rear ends thereof, the legs 40 at the rear end of the platform being extended to a point above the same, a sill supported between the extended ends of the rear legs and above the platform, an arm extending transversely of the sill and having pivotal connection intermediate its ends to the sill, one end of the arm being disposed over the forward end of the platform, an oscillating hand lever mounted on the platform adjacent the arm, a rod pivotally connected at one 45 end of the lever and extending forwardly therefrom, an agitator element carried by the said forward end of the arm and including a plurality of downwardly diverging agitator fingers and a pulley element, and a flexible cable connected at its ends to remote points on the rod and having its intermediate portion wrapped about said pulley.

2. A hand operated washing machine, comprising a base structure in the form of a 50 platform, supporting legs for the platform at the front and rear ends thereof, the legs at the rear end of the platform being extended to a point above the same, a sill supported between the extended ends of the rear 55 legs and above the platform, an arm extend-

ing transversely of the sill and having pivotal connection intermediate its ends to the sill, one end of the arm being disposed over the forward end of the platform, an oscillating hand lever mounted on the platform adjacent the arm, a rod pivotally connected at one end of the lever and extending forwardly therefrom, an agitator element carried by the said forward end of the arm and including a plurality of downwardly diverging agitator fingers and a pulley element, a flexible cable connected at its ends to remote points on the rod and having its intermediate portion wrapped about said pulley, a hook member carried by the arm adjacent the end thereof remote from the agitator element, and an eye carried by the platform for engagement by said hook to maintain the agitator carrying end of the arm in lifted position.

3. In mechanical washing apparatus of the character described, a supporting structure, an arm member disposed across said supporting structure, a hinge connection between the supporting structure and the arm adjacent one end of the arm, the other end of the arm being designed to overlie a clothes receptacle, a shaft extending through the said other end of the arm and rotatable therein, a pulley upon the upper end of the shaft overlying the arm, a head secured to the lower end of the shaft beneath the arm, a plurality of fingers carried by said head and extending downwardly from the arm in divergent relation, a lever vertically disposed at one side of the arm adjacent the hinge connection of the same with the support, a pivotal connection between the lower end of said lever and an underlying supporting structure permitting oscillation of the lever in a path extending longitudinally of the arm, a bar member pivotally attached at one end to said lever at an elevation in the same plane as said pulley, an elongated flexible member connected at its ends to said bar and having its intermediate portion wrapped about the pulley, the said end of the arm adjacent the hinge connection facilitating the oscillation of the arm to raise the elements at the opposite end thereof from a clothes receptacle, and means for coupling the end of the arm adjacent the hinge to the supporting structure to maintain the other end of the arm in raised position.

In testimony whereof we hereunto affix our signatures.

ALEXANDER LOUVIER.
MARIUS LEWIS LOUVIER.
